(57) **CLAIM**

The ornamental design for a vapor transfer cartridge for use in a respiratory therapy system, as shown and described.

DESCRIPTION

FIG. 1 is a perspective view from the top, front and left of a vapor transfer cartridge for use in a respiratory therapy system;

FIG. 2 is a perspective view from the top, rear, and right side thereof;

FIG. 3 is a front elevation view thereof;

FIG. 4 is a rear elevation view thereof;

FIG. 5 is a left side elevation view thereof;

FIG. 6 is a right side elevation view thereof; and,

FIG. 7 is a top view thereof.

The bottom view of the vapor transfer cartridge is the same as the top view thereof. The broken-line portions of the vapor transfer cartridge for use in a respiratory therapy system in FIGS. 1-7 are shown for illustrative purposes only and form no part of the claimed design.
